COLLAR AND CUFF

Filed Aug. 22, 1924

Inventor
O. Roberts
By Robert C. Lehman
H. C. Myers

UNITED STATES PATENT OFFICE.

ODIN ROBERTS, OF BOSTON, MASSACHUSETTS.

COLLAR AND CUFF.

Application filed August 22, 1924. Serial No. 733,543.

My invention relates to the construction of folding collars or cuffs; the objects in view are the provision of means whereby any degree of stiffness of such articles of wearing apparel (within the practicable or desirable limits) may be imparted to them, together with simple means to enable them to fold easily and with certainty along a predetermined line of fold, which may be curved or straight; simplification of washing and cleansing operations; the elimination of ephemeral stiffening material such as starch; by the assemblage as an integral whole, of a plurality of layers of textile fabric and by inclusion in the body of the collar or cuff of a permanently resident elastic colloidal material; reductions in cost of manufacture by the employment of relatively cheap and coarse grades of textile fabrics in those portions of the collar or cuff which are not exposed to view, while it is in use, associated with a minimum of relatively costly or fine-textured fabric in the normally visible surfaces of the article; and, in general, the production of a collar or cuff inherently durable, comfortable, presentable, and easily cleansed after becoming soiled by wear.

As representative of all such articles of manufacture a folding or turn-over collar is selected for purposes of illustration.

The collar, exemplifying the improvements herein to be described, belongs to the genus suggested by such United States patents as Hilton No. 216,039, France, No. 425,129; Hyatt, No. 419,257, and comprises an adhesively assembled laminated fabric of the genus suggested in the United States patent to Andrews, No. 433,388.

In the drawings hereto annexed, which illustrate my invention as applied to the fabrication of a folding or turn-down collar, Fig. 1 represents, in plan, a collar, unfolded.

Fig. 2 a section of a collar, as on the line 2-2 of Fig. 1;

Fig. 3 a similar section showing a variant of the collar fabric;

Fig. 4 a fragmentary section at the edge of a blank of collar fabric;

Fig. 5 a section similar to that of Fig. 4, showing how one of the components of the fabric may be shaved or skived to form a turning edge;

Fig. 6 a similar section showing a skived

edge turned back over the body of the fabric;

Fig. 7 a fragmentary edge section of a collar, showing the edge of the fabric, of full thickness, turned back over and stitched to the body of the fabric;

Fig. 8 a fragmentary section of collar fabric, illustrating how components of different texture may be assembled;

Fig. 9 a vertical section of a collar, folded as when worn;

Fig. 10 a fragmentary section across the fold line of a collar, illustrating the manner in which the inner fabric component, partially cut or severed, may be guarded against raveling or furring.

The fabric which constitutes the collar, preferably as a whole, as indicated in Fig. 1 is a compound structure, characterized by plies of woven cloth, adhesively integrated, preferably by means of a colloidal cellulose derivative produced by converting a portion of the cellulose fibre of one or more of the plies superficially, and causing the cellulose derivative to join and integrate the plies. If, as is usual, it is considered desirable to have the external and visible surface of the completed collar present the aspect and texture of the original fabric, this outer ply at least will be so treated that the external and finally visible parts of the fabric will not be affected by the reaction by which the colloidal cellulose derivative is produced. And, if as may be the case, the adhesive (such as a cellulose ester in a volatile solvent) be prepared otherwise than by conversion of part of the fabric-fibre and be applied to and between the fabric plies, the consistency, and quantitative distribution of the adhesive should be such that it will not penetrate so far into a fabric ply as to alter the visual appearance of its outer surface, provided such alteration is to be avoided. But, should it become desirable in special cases to produce the glossy and parchment-like appearance which characterizes fabrics converted partly into, or coated with, colloidal cellulose derivative, either or both of the constituent plies which are united to form the compound fabric may be treated, or coated, on both sides.

The body and stiffness of the compound fabric will vary with the weight and texture of the constituent plies, and to some extent with the specific character and

amount of the adhesive colloid employed. For the purpose of making a collar fabric in the manner indicated, two plies of cotton fabric of fairly fine yarn and close weave, 5 will serve practically; for reasons to be set forth, it is preferred to employ a fine-textured fabric for the visible or face ply, and a stouter bodied and coarser cloth for the inner or back ply.

10 With economy of time and labor in the manufacture of the collar in view, it is considered advisable to make the compound fabric out of broad goods, treating the plies to form the colloidal cellulose derivative on 15 one side of either or both of the plies, and then assembling them between rollers under adequate pressure to integrate them by means of the adhesive. The plies thus united will then be treated in such manner 20 as to fix the colloidal adhesive and to prevent the formation of a greater amount of the cellulose derivative than is desirable.

A number of reagents, capable of 25 converting cellulose fibre into colloidal derivatives, are known and available, as also are solutions in volatile solvents, of such cellulose derivatives. These derivatives differ in details of physical characteristics: some, when permanently fixed, are stiffer and less 30 elastic than others. The choice of reagent and cellulosic product will therefore be determined by the desired physical characteristics of the end-product, as represented by a collar or cuff.

35 Thus will be produced a sheet of integrated laminated material, susceptible of being handled in the same way as any unitary textile fabric for collar manufacturing purposes, as by cutting blanks either 40 for parts of collars or entire collars.

To make a collar such as is illustrated in Fig. 1 a blank is first cut from laminated, 45 adhesively integrated material of the character above described, this blank being of such shape and size as to include in one piece the band portion B, the top or fold over portion T, and marginal portions which when turned back upon the body of the collar, form the turned and doubled 50 margins L. Before the margins of the blank are turned, the fabric is scored or otherwise rendered more flexible, along the line of fold, at F. The inner or back-ply C of the fabric (Fig. 2) is grooved at F, 55 so that enough of its material is removed to render the fabric as a whole readily and neatly flexible along the line of groove. This grooving or local linear weakening may be effected in any one of several ways: 60 The blank of laminated fabric may be passed under a thin emery wheel, which will grind the groove, or under a rotary cutter which will cut out the groove. Or, the ply C of the fabric may be weakened in its 65 fibre by contact with a heated grooving im-

plement, maintained at a temperature high enough to deteriorate the fibre of the ply C, in part. Such deterioration by heat does not necessarily involve charring of the fibre and need not, therefore, disfigure it. 70 Preferably, and as indicated by the drawings, the local reduction of the back-ply should be regulated so that the outer ply and the integrating adhesive between the plies, will be unaffected. Thus not only the 75 full strength of the outer ply will be conserved, but the supplemental support of the adhesive also.

The groove F, which may extend only 80 part way through the material of the back-ply C, provides a line on which the relatively heavy-bodied collar material will fold easily and smoothly. After the collar blank has thus been grooved, it will be finished by such manufacturing processes as 85 turning and edge stitching, and buttonholing. This is of particular importance in connection with adhesively-integrated two- 90 or more-ply fabrics adapted to be laundered in usual ways, as are the collars or the like of this specification. Inevitably the laundry operations involve flattening the collar to the state shown in Figs. 1 and 2, wetting, and agitation; and refolding on line F; these flexings are peculiarly liable 95 to break the adhesion between plies if the point of flection is at any part in which the inner ply at the fold or crease is of substantially greater thickness than the outer 100 ply at the fold or crease. Separation or blistering between the plies at and near the fold is a detriment to the collar, and an important utility of the mechanically-reduced thickness of the otherwise uniform inner 105 ply at the fold is to prevent any 110 tendency to separation or blistering.

If it is desired to provide a thin edge-finish on the collar, the margins of a blank 115 may be shaved or skived, as illustrated in Figs. 4, 5 and 6. The fabric-blank, shown at its edge in Fig. 4 lends itself to manipulation in a manner analogous to leather. A skiving machine, such as is used in the manufacture of shoes and other articles fabricated of leather, may be employed to cut away the back-ply C, (or as much of it as is desired,) leaving the face-ply C' projecting as a thin ledge L around the margins of the collar blank. This ledge L may then be turned back over the back-ply C (see 120 Fig. 6) and be secured thereto either by adhesive, or by stitches. Should the laminated fabric be three-ply, as indicated in Fig. 3, the skived edge will lap over and be secured to the third ply C'. There are, 125 however, structural advantages in a relatively thick and therefore stiff turned edge, which constitutes in effect a frame, emphasizing and maintaining the marginal contour of the collar. Further, it produces 130

a thickness at the edges of the collar which lends an appearance of substantiality. I therefore believe it to be preferable to leave the cut margin of the collar blank as it is shown in Fig. 4, and to turn this margin, in its entire thickness, upon the body of the collar, securing it by adhesive, or by stitching, as indicated in Fig. 7.

The total thickness of the collar fabric may be brought to any desired measure by employing coarser and heavier fabric for the back-ply as an alternative to using more than two plies of thinner fabric. In Fig. 8 the relationship of a thick back-ply C to a thin face ply C' is conventionally illustrated. If the mode of reducing the material along the fold line at F and the structure of the back ply be such that there is fraying or furring of the cut or abraded fibres, these may be laid and secured in place by applying a thin stripe coating of adhesive material F' (Fig. 10) over the cut or abraded fibres. A cellulose ester in a volatile solvent will serve this purpose. Or, since the back ply C will not be exposed to view while the collar is in use, the preliminary treatment for the formation of an adhesive cellulose derivative by reaction on part of the fibrous structure may be carried out by immersing the back-ply fabric completely in the reacting liquid, or allowing the reacting liquid to penetrate deeply into the fabric from one side, so that the fibres thereof will be partly parchmentized or converted nearly or wholly throughout. In such case, the scoring or abrasion to form the fold line groove F will produce little or no tendency toward fraying or furring of the fibre.

When it is rendered permanent by appropriate treatment, the colloidal adhesive with which the plies of the laminated fabric are integrated becomes, in effect, an in destructible sizing, which lends a measure of elastic stiffness to the fabric as a whole. The degree of such stiffness may be increased or diminished by regulation of the consistency and quantity of the colloidal adhesive. And, if a gloss, or clear light-reflecting surface (such as characterizes a completely starched and ironed collar) be desired, the face ply may be subjected to the solvent reagent on both sides or deeply penetrated from one side so as to produce as much conversion of the normally visible face ply surface as may be desired.

A collar, made in the manner above described, may be cleansed thoroughly by ordinary washing and rinsing, and if laid to dry on some smooth flat surface, will restore itself on drying to its original condition though hot ironing is to be recommended. The provision of the scored fold line enables the collar to fold neatly and sharply in its designed contour, and thus

imposes on the collar the appropriate shape to secure a proper fit on the wearer's neck.

I use the word "collar" in the claims here-to appended, as including not only a collar to be worn on the neck, but also such analogous articles as cuffs.

What I claim, and desire to secure by Letters Patent, is

1. A folding collar comprising a blank of laminated textile fabric composed of adhesively integrated plies each including within its area, the top and band portions and fold line of the collar, the inner ply of said blank being locally reduced along said fold line to predetermine the fold of the collar. 75

2. A folding collar, comprising a blank of laminated fabric of which the plies are adhesively integrated, textile fabrics of differing characteristics, one of said plies being of relatively thick fabric, said thicker 85 ply locally reduced to produce a determinate line of fold to constitute a relatively flexible region capable of being repeatedly flexed without causing separation of the adhesion between plies.

3. A folding collar, comprising a blank of laminated fabric of which the plies are adhesively integrated, and having one of said plies locally reduced through part of its thickness to produce a determinate line 90 of fold, leaving the other ply and the region of adhesive contact unaffected.

4. A folding collar, comprising a blank of laminated fabric of which woven textile fabric plies are adhesively integrated by 100 means of a colloidal cellulose derivative, and having one of said plies locally reduced to provide a linear region capable of being repeatedly flexed without inducing separation of the adhesion between plies at or near said 105 linear region.

5. A folding collar, comprising a blank of laminated textile fabric of which plies are conjoined adhesively by a colloidal cellulose derivative, one of said plies being of relatively thick fabric, said thicker 110 ply being severed through a part of its thickness and thereby locally reduced to produce a determinate line of fold.

6. A folding collar, comprising a blank 115 of laminated textile fabric of which the plies are adhesively integrated by means of a colloidal cellulose derivative, and having one of said plies locally reduced through part of its thickness to produce a determinate line of fold, leaving the other ply and the region of adhesive contact to be flexed upon folding. 120

7. A folding collar, comprising a blank 125 of laminated textile fabric of which plies are adhesively integrated by means of a colloidal cellulose derivative, one of said plies being of relatively thick fabric, said thicker ply being cut away within its thickness to enable folding at a determinate line of fold, 130 without setting up forces tending to separate

the adhesion between plies, and leaving the other ply and the region of adhesive contact unaffected.

8. A folding collar made up of several plies of textile fabric adhesively united, one of the plies being thicker than another, and having a portion severed therefrom through a part of its thickness at a line of fold, the remaining thickness of the fabric constituting a flexible portion in which the remainder of the thicker ply is not substantially thicker than the thinner ply.

9. A folding collar, comprising a blank of laminated textile fabric of which the plies are adhesively integrated, and having one of said plies locally reduced to produce a determinate line of fold, and having the fibres of said ply in the region of local reduction adhesively secured together.

10. A folding collar, comprising a blank of laminated textile fabric of which the plies are adhesively integrated, one of said plies being of relatively thick fabric, said thicker ply being locally cut away within its thickness to enable folding on a determinate line

of fold and having the fibres in the region of local reduction adhesively secured together.

11. A folding collar, comprising a blank of laminated textile fabric of which the plies are adhesively integrated, and having one of said plies locally reduced by removal of a portion of its substance through part of its thickness only to produce a determinate line of fold, leaving the other ply and the region of adhesive contact unaffected and having the fibres in the region of local reduction adhesively secured together. 35

12. A folding collar, comprising a blank of laminated fabric of which the plies are adhesively integrated, one of said plies being 40 of relatively thick fabric, said thicker ply locally reduced through part of its thickness to produce a determinate line of fold, leaving the other ply and the region of adhesive contact unaffected and having the fibres in 45 the region of local reduction adhesively secured together.

Signed by me at Boston, Massachusetts,
this twentieth day of August, 1924.
